MATCH BOX HOLDER FOR FIREPLACE TYPE MATCHES

Martin Field, 1346 N. McCadden Place, and John Bereznak, 147 N. Ave. 18, both of Los Angeles, Calif. 90028

Filed Dec. 30, 1971, Ser. No. 214,516

Term of patent 14 years

Int. Cl. D7—08

U.S. Cl. D48—28

FIG. 1 is a front right perspective of a match box holder for fireplace type matches showing our new design; FIG. 2 is a left side elevational view;

FIG. 3 is a rear elevational view;

FIG. 4 is a top plan view;

FIG. 5 is a bottom view;

FIG. 6 is a perspective view of a modified form of the match box holder for fireplace matches shown in FIG. 1, the modification being the omission of the support stand;

FIG. 7 is a left side elevational view of FIG. 6;

FIG. 8 is a top plan view of FIG. 6; and

FIG. 9 is a bottom plan view of FIG. 6.

We claim:

The ornamental design for a match box holder for fireplace type matches, as described.
